BOMB

Henry Stieb, Berkey, Ohio

Application July 12, 1941, Serial No. 402,199

1 Claim. (Cl. 102—2)

The present invention relates to improvements in bomb construction.

An object of the invention is to provide a bomb of generally improved design.

Another object of the invention is the provision of a bomb designed to afford increased penetrative power.

A further object of the invention is to provide a bomb constructed so that upon impact thereof an armor piercing missile is discharged therefrom.

Still another object of the invention is the provision of a bomb of the aforesaid character which is equipped with a safety catch adapted to preclude accidental discharge of the shell or missile carried by the bomb.

Other objects and advantages will be apparent from the following description and appended claim.

In describing my invention in detail, reference will be had to the accompanying drawing illustrating a practical adaptation of the invention, and in which:

Figure 1 is a side elevational view of the improved bomb set for release,

Figure 2 is a longitudinal section through the same,

Figure 3 is an elevational view of the rear end of the bomb, and

Figure 4 is a fragmentary longitudinal section taken on line 4—4 of Figure 1.

With reference to the drawing, wherein like characters of reference denote corresponding parts throughout the several views, B generally designates the body of the bomb which is transversely divided, intermediate its ends, to provide a front section 10 and a rear section 11. These sections are advantageously shaped to provide, in assembly, an exterior contour of approximately tear-drop configuration.

The front body section 10 is mainly of cylindrical formation tapered at the front end to provide a pointed nose 12 with the reduced rear end portion terminating in a flat end face. This section is formed with an axial bore opening through the nose and designated by the numeral 13. Adjacent to rear end the bore 13 merges into an enlarged interiorly screw fitted counterbore 14. At the front and rear portions of the forward body section 10 are formed, at diametrically opposed sides, radially projecting pairs of guide ears 15 and 16 respectively.

The rear body section 11 has a gradually diminishing taper toward the rear end which ter-

minates in a rounded tail portion 17. The forward end of this rear section is shaped to provide an exteriorly threaded stud 18 adapted to engage the socket afforded by the counterbore 14, while an annular flat surface about the stud is designed to assume abutting relation with the flat end of the forward section. The intermediate portion of the body section 11 is hollowed to form therein a longitudinally elongated tapered chamber 19 while aligned bores 20 and 21, of relatively small diameter, are formed through the end portions and in communication with the intermediate chamber.

Mounted to extend axially through the body section 11 and slidable longitudinally in the bores 20 and 21 thereof is an elongated pin 22 advantageously tapered at the inner end and formed with a reduced section within the chamber forming an abrupt shoulder 23.

Above the shoulder 23 the pin is provided with a fixed collar 24 while at the rear end is formed an elongated loop 25. About the pin 22 is sleeved a spring 26 compressed between the rear end wall of the chamber 19 and the collar 24 adapted to yieldingly urge the pin to a forwardly projected firing position. In the tail end 17 of the bomb is formed a longitudinally directed slot 26' opening into the rear and adapted to accommodate the loop 25 therein to allow extension of the pin 22. In the rounded end of the tail 17 are also provided, at each side of the slot 26, a pair of complementary notches 27 designed to receive the inner end of the loop 25 therein when it is disposed in a position at right angles to its set firing position for locking the pin in safety arrangement.

Through a pair of apertures 28 in opposed sides of the section 11 are extended a pair of levers 29 fulcrumed on pins 30 extended through apertures in the intermediate portions of these levers so as to provide an arm of each lever inward of the section and an arm projecting outwardly thereof. A pair of compression springs 31 mounted in the forward end of the chamber 19 bear against the inner arms of the levers 29 to yieldingly force the same against stop projection 32 and tend to hold these levers in approximate radial positions. These springs also act to maintain the inner ends of the levers against the shoulder 23 of the firing pin to maintain the pin in rearward retracted position against the opposite action of a spring 26 sleeved about the pin between its rear end and the collar 24 and tending to project the pin forwardly.

In the guide elements 15 and 16 at each side of the front bomb section 10 is slidably mounted a longitudinally extending trip rod 34 disposed parallel with the axis of the bomb so that its inner end is in registration with and adjacent the outer end of each lever 29 while its outer end protrudes forwardly of the foremost part of the bomb body. On each of these trip rods 34 are provided a pair of fixed collars 35 and 36, a compression spring 37 being sleeved about the rods between the guide 16 and the forward collar 37 to urge the rod forwardly to a position limited by the rearward collar 35 which bears against the guide 16.

Within the bore of the bomb is carried a missile firing charge C, which may be of cartridge type formed with a flanged cap at its inner end. This charge device is disposed so that the cap flange rests against the shoulder at the inner end of the bore 13 while the explosive and missile carrying shell portion extends along this bore from the inner end to approximately its medial portion. At its inner end this charge device is provided with a percussion cap centrally thereof which assumes alignment with the inner end of the bore 20 guiding the firing pin. The outer end of the bore 13 is advantageously closed by a conical cover cap 36 which keeps the bore clean and reduces air resistance.

The rear body section 11 may advantageously be formed of longitudinally split complementary parts mated, in assembly, by fastening pins or rivets 38, to facilitate assembly of the firing mechanism therein. This rear portion of the bomb body may also be equipped with radially and rearwardly directed fins 39 to accurately guide the bomb as it is directed toward its target, as from an aircraft.

Until the bomb is set in preparation for release the firing pin is locked in non-firing safety position by disposing the end loop 25 in registration with the shallow grooves or notches 27, as shown at Figure 4. In preparation for release this loop is turned to a right angular position in registration with the deep slot 26', the pin 22 being yieldingly held in retracted non-firing arrangement by the action of the compression spring 31 against the inner arms of the

levers which engage the shoulder 23 of the pin and compress the pin projecting spring 26. When the bomb strikes its objective the impact initially retracts the actuating rods 34, which 5 protrude forwardly of the bomb body, to compress the springs 31 and swing the outer arms of the levers 29 rearwardly to cause forward swinging movement of the inner arms to release the firing pin which is pressed forward 10 by the spring 26 so that its forward pointed end strikes against the percussion cap of the charge carrying cartridge like member C. This action effects explosion of the explosive or projecting charge and discharge of the missile or projectile 15 which travels through the forward end of the bomb bore 13 and discharges through the nose thereof. As a result of this action the bomb is exceptionally effective for the penetration of armor or other bodies and is particularly efficient 20 in the bombing of naval craft.

It is to be understood that the invention is not confined to the specific construction, arrangement or use illustrated and described and that considerable modification may be made 25 therein within the spirit of the invention as defined by the appended claim.

Having thus described my invention, I claim:

In a bomb of the character described, a body 30 having an axial bore opening through the front thereof, a missile mounted in the said bore, a charge for projecting the said missile through the bore and the front of the body, a firing pin slidably mounted in the rear portion of the body and operable to fire the charge, a spring yieldingly urging the firing pin to charge firing position, a pair of pivoted levers mounted on the body releasably engaging the pin, spring means 35 acting to hold the levers against the pin to retain the latter in retracted non-firing position, a 40 pair of operating rods slidably mounted at the sides of the body, the said rods disposed to protrude forwardly of the body and operable to engage the levers to swing the same to firing pin releasing positions, and springs yieldingly holding the said rods in extended non-releasing positions.

HENRY STIEB.
